UNITED STATES PATENT OFFICE.

ELBERT R. WINSLOW AND CLYDE A. JONES, OF KEARNEY, NEBRASKA.

PORTABLE ELECTRICAL DEVICE.

1,222,827.

Specification of Letters Patent. Patented Apr. 17, 1917.

Application filed March 20, 1916. Serial No. 85,440.

To all whom it may concern:

Be it known that we, ELBERT R. WINSLOW and CLYDE A. JONES, citizens of the United States, residing at Kearney, in the 5 county of Buffalo and State of Nebraska, have invented certain new and useful Improvements in Portable Electrical Devices, of which the following is a specification.

This invention relates to new and useful 10 improvements in a portable electrical device for use in offices, homes and by travelers and comprises an electrical fan and an electric incandescent light mounted on the same frame and provided with a socket by 15 which the device may be attached to a bracket, electrolier, drop cord or wherever an incandescent light bulb can be made to glow.

The primary object of the invention is to 20 combine in a single article which is both small and light and may be transported readily in an ordinary valise, an electric motor driven fan and an electric light, each included in an independent circuit connected to contacts in the socket, and a key adapted to operate a movable member in connection with or adapted to be connected to lead wires carrying current, said member when moved by the key in different directions 25 and at different distances cutting in either the fan motor alone, the light alone, or both simultaneously. Both may also be cut out of circuit when desired.

Another object resides in the provision of 30 a unitary device embodying an electrically driven fan which is inclosed within a frame and on which frame an electric lighting device is supported.

Other objects of the invention will be set 40 forth in the following description and pointed out in the appended claims, reference being had to the accompanying drawings in which:

Figure 1 is an elevation partly in section 45 of the improved device,

Fig. 2 is a horizontal sectional view of the same on the line 2—2, and,

Fig. 3 is a detail sectional view on the line 3—3 of Fig. 1.

Fig. 4 is a detail view showing the circuit closing device in position for switching the current to the fan,

Fig. 5 is a similar view showing the device in position for closing the circuit 55 through the lamp,

Fig. 6 is a detail sectional view illustrating

ing the switch in position to render both the electric lighting device and the fan active.

Referring to the drawings in which similar reference characters denote like parts throughout the several views, 10 designates an electric motor of any improved type on the shaft 11 of which is mounted a fan 12 adapted to rotate with the motor. Inclosing the motor 10 is a casing 13 of any suitable form, but as shown formed in two parts 14 and 15, the upper part 15 having a flange 16 on its lower end to fit over the part 14, a set screw 17 securing the two parts together.

At the bottom of the casing 13 on opposite sides thereof are outwardly projecting bosses 18 in which are fastened the ends of two tubes 19, said tubes extending horizontally from the casing a short distance beyond the wings of the fan 12, then turning downwardly as at 20 to a point below the fan, turning inwardly once more as at 21 to a point near the axis of the motor where they are attached to a lamp socket 22. Conducting wires 23 and 24 lead from a lamp 25 mounted in said socket through the bent tubes 19, 20, 21 into the motor casing 13, to a socket 26 on the top of the casing 13.

Projecting from the motor casing at the center thereof is a threaded hollow neck 27 upon which the enlarged lower end 28 of the socket 26 is screwed.

The socket 26, as shown is made of some insulating material such as porcelain, on the upper end of which is fastened a sleeve 29 made of metal. A metal stud 30 is fastened to the socket at the center thereof and these two metal parts serve to make contact with the terminals of the circuit 90 wires in a manner similar to the ordinary socket found on brackets, electroliers and the like. Within the socket 26 is a suitably formed cavity 31 containing two sliding plates 32 and 33, the plate 32 having 100 two offsets 34 and 35 while like offsets 36 and 37 are formed in the plate 33. The upper ends of the plates 32 and 33 are connected by suitable wires with the contacts 29 and 30 on the outside of the socket. A 105 block 38 made of insulating material connects the two plates 32 and 33 so that when the block is moved, the plates move in unison therewith. For the purpose of moving the block and its attached plates, a key 39 110 extends transversely through the socket and through a horizontal slot 40 in the block,

said key having a bit 41 in the form of a crank bend lying within the slot in such position that when the key is turned by the thumb piece 42 the plates 32 and 33 may be 5 raised or lowered. It is to be understood that the plates 32 and 33 will be provided with suitable guides to direct them in their upward and downward movement. Such guides have been omitted in the drawings 10 for the sake of clearness.

Within the cavity 31 of the socket 26 are fastened two contact plates 43 and 44, said plates forming the terminals of the wires 23 and 24 leading from the electric light 25. 15 The free ends of the terminals project into the offsets 35, 37 of the plates 32, 33 in position to contact with said plates when they are moved downward by the key 40. Like contact plates 45, 46 are secured to the socket 20 above the former contacts, their free ends projecting into the offsets 34, 36 of the sliding plates in position to make contact therewith when said plates are moved upwardly. These upper contact plates form the terminal 25 of wires 47, 48 that connect with the commutator of the motor 10.

The device as shown and described is simple, compact and convenient, readily transportable and may be connected for use to 30 any socket capable of holding an incandescent light. When in position with the key 40, placed as in Fig. 3, the current will be cut out from both the fan and the electric light. If it be desired to set the fan in motion, the key is turned sufficiently far to move the sliding plates 32, 33 upward until the offsets 34 and 36 in said plates come in contact with the terminals 45, 46, as shown in Fig. 4. To cut out the fan and cut in 40 the light the key is turned in an opposite direction to lower the sliding plate, see Fig. 5, thereby breaking contact with the terminals 45 and 46 and connecting them with the terminals 43 and 44, the current 45 passing thence by way of wires 23, 24 to the electric light 25. When it is desired to use the light and fan simultaneously, an extreme movement of the key in either direction will move the offsets 34 to 37 on the two sliding 50 plates in contact with both sets of terminals 43, 46, thus switching both light and fan in circuit.

A simple portable device such as described is easily carried about and applied to 55 a socket over or at one side of a desk or table and either light, fan or both used as desired. When traveling the fan may be packed in a valise and used wherever the traveler stops if the place be wired for electric lighting.

60 The tubular frame incloses the fan, supports the electric lighting device and receives and conceals the circuit from the lighting device to the motor casing. A frame member 50 connects the portions 20 65 of the tubes 19 of the tubular frame.

From the foregoing description taken in connection with the accompanying drawings, it is thought that the construction and operation of the device will be clearly understood, and while we have herein shown and described certain specific embodiments of our invention, we do not wish to be limited thereto except for such limitations as the claims may import.

We claim:

1. In a portable electrical device of the kind described, the combination with a motor driven fan and an electric light connected to the frame of said fan, of a socket projecting upwardly from said fan frame 75 and adapted to be removably engaged with an incandescent light socket to support said device and to make electrical contact therewith, independent circuit wires extending from the electric light to a pair of contacts 80 in the first named socket, a second pair of independent circuit wires running from the fan to a second pair of contacts also in the socket, and a circuit closing device adapted to optionally close the circuit through the 85 electric light, the fan or through both.

2. In a portable electrical device of the kind described, the combination with a motor driven fan and an electric light, of a casing inclosing the motor of said fan 90 and supporting said light, a socket projecting upwardly from said casing to sustain both fan and light from an incandescent light socket and to supply them with an electric current, circuit wires from the motor 100 secured to terminals within the first-named socket, separate circuit wires from the electric light also entering said socket and secured to other terminals, and a circuit closing device adapted to engage said terminals 105 for optionally energizing the fan or the electric light, or energizing both fan and light.

3. In a device of the kind described, the combination with an electric light and a motor driven fan, of a casing for the motor 110 of said fan, and a socket projecting upwardly from said casing, a socket for the electric light, tubular supports connected to the motor casing and to the lamp socket looped around said fan, circuit wires from 115 the motor connected to terminals within said socket, circuit wires from the lamp passing through said tubular supports into the motor casing and thence to terminals in the socket, and a sliding member adapted to make contact with one or both sets of terminals.

4. In a device of the kind described, the combination with an electric light and a motor driven fan, of a casing inclosing the motor of said fan and a socket projecting upwardly from said casing, a socket for said electric light, a tubular frame supporting said lamp socket attached to the motor casing, said frame being looped around the fan, independent circuits from the light and 120 125

from the fan leading into said socket and there attached to insulated terminals, and means operated by a key adapted to be connected with an electric current for rendering 5 either the light, the fan or both active.

5. The combination of an electric motor and a casing therefor adapted to be connected to an electric lamp socket, a fan driven by the motor, a tubular frame connected 10 to the casing and inclosing the fan, an electric lighting device connected to the frame, an electric circuit extending from the lamp through the tubular frame into said casing, and an electric switch to control the 15 motor.

6. The combination of an electric motor and a casing therefor adapted to be connected to an electric lamp socket, a fan driven by the motor, a frame connected to 20 the casing and inclosing the fan, and an electric lighting device connected to the frame, said parts forming a unit attachable to and detachable from the lamp socket.

7. The combination of an electric motor and a casing therefor, a fan driven by the 25 motor, a frame connected to the casing and inclosing the fan, and an electric lighting device supported on the frame.

8. The combination of an electric motor and a casing therefor adapted to be connected to an electric lamp socket, a fan driven by the motor, a frame connected to the casing and inclosing the fan, an electric lighting device connected to the frame, said parts forming a unit attachable to and de- 30 35 tachable from the lamp socket, and means for rendering either the fan or the lighting device, or both, active.

In testimony whereof we affix our signatures in presence of two witnesses.
